Primary Examiner — Mark Goodwin(74) *Attorney, Agent, or Firm* — Shannon V. McCue; Hahn, Loeser & Parks, LLP(57) **CLAIM**

The ornamental design for a diesel emissions fluid tank, as shown and described.

DESCRIPTION

FIG. 1 is a perspective view showing the ornamental design of the diesel emissions fluid tank according to the invention;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof with the bottom surface being unornamented.

The broken lines shown are environmental only and form no part of the claimed design.
